A. J. WEISS.
CONCEALED FASTENING FOR WALL FIXTURES.
APPLICATION FILED NOV. 24, 1915.

1,243,664.

Patented Oct. 16, 1917.

Inventor
Amedee J. Weiss
By his Attorney
James S. Bachow

UNITED STATES PATENT OFFICE.

ARTHUR J. WEISS, OF WEST ORANGE, NEW JERSEY, ASSIGNOR TO EDWARD A. MCCOY,
OF EAST ORANGE, NEW JERSEY.

CONCEALED FASTENING FOR WALL-FIXTURES.

1,243,664.

Specification of Letters Patent.

Patented Oct. 16, 1917.

Application filed November 24, 1915. Serial No. 63,207.

To all whom it may concern:

Be it known that I, ARTHUR J. WEISS, of the town of West Orange, county of Essex, and State of New Jersey, have invented a certain new and useful Improvement in Concealed Fastenings for Wall-Fixtures, of which the following is a specification, reference being had to the accompanying drawings, which form a part of the same.

10 An object of my invention is to provide means for affixing electric fixtures to a wall, partition or support in such a manner that the securing means will be concealed, thus doing away with attaching screws, rivets, 15 nails or other unsightly securing elements.

Another object of my invention is to provide means for securing fixtures to their supports in such manner that they may be readily disengaged for any purpose such as 20 cleaning, repairing or shifting to another connection without the necessity of disturbing the wiring adapted to connect with said fixtures when in place.

Other objects of my invention will be apparent hereinafter.

Referring to the drawings:

Figure 1 is a vertical cross section of an electric light fixture embodying my invention;

30 Fig. 2 is a back view of the fixture shown in Fig. 1;

Fig. 3 is a detailed sectional view of my fastening element showing also the electrical connection, as such connections are now 35 commonly made;

Fig. 4 is a partial cross section of Fig. 3 taken along an imaginary line near the top of Fig. 3;

40 Fig. 5 is a cross section of my fastening element showing a modification of the electrical connection adapted to be used in connection with my improved wiring system described in my application for United States Letters Patent Serial No. 34,825, filed 45 June 18th, 1915.

Referring now in detail to the drawings, 1 represents a plate or shield of a fixture, attached to the back of which, either by brazing, welding, casting, or in any other 50 well-known manner, are offsets 2 to which is screwed or otherwise secured a bridge element 3, in which are placed the binding

posts 5, having the projecting connections 6. These connections are adapted to fit into the conducting sleeves 7 and thus make electrical connection with the binding posts 8, which may be in the usual way connected with the source of electric supply.

An outlet box 10 is shown having a projection 11 and a threaded stud 12 extending therefrom. Onto this threaded stud is screwed or otherwise secured, a coupling 13. This coupling is provided with shoulders 14 and a projection 15.

For use in connection with the common 65 method of wiring, this coupling 13 is usually made of insulating material with the sleeves 7 being made of conducting material and inserted therein as shown. Of course this coupling 13 may be made of conducting 70 material in which case the sleeves would be made of insulating material and the projections from the binding posts 5 would be in electrical contact with the binding posts 8. In Fig. 5 I have shown a coupling adapted 75 for use in connection with my improved system of wiring described in my co-pending application for United States Letters Patent above referred to. In this case the coupling is made of conducting material 80 while the inserted sleeve 16 is made of mica or other non-conducting material.

In operation my device may be described as consisting of three elements, namely, the bracket element to the back of which is securely attached the bridge having an opening 17, and in which bridge the wiring is connected as shown, the second element is the coupling 13, and the third element is the projection 12 from the support or outlet box 90 10. In order to place in position a fixture having the connections herein described, the coupling 13, which is preferably screw threaded is screwed onto the threaded projection 12 of the outlet box 10, into its desired position. The bracket is then fitted over the outlet box, the projecting ends 6 fit into the sleeves 7, and the projection 15 fits under the bridge 3. The fixture is now securely in place, and the electrical connections are now made.

In the above description and the accompanying drawings I have shown a preferable embodiment of my invention but I do

not wish to be confined to the disclosure therein contained but what I desire to cover by Letters Patent is set forth in the appended claims.

5. "Claims:

1. In concealed fastenings for wall fixtures, a plate having a bridge fitted to the reverse side thereof, electrical connections extending through said bridge and projecting therefrom, said electrical connections being insulated from said bridge, a threaded coupling element of insulating material, having conducting connections therein adapted to coöperate with said projections from the electrical connections, and further electrical connections adapted to lead from said coupling; an outlet box, and a threaded projection from said outlet box, on which said coupling is adapted to be screwed.
10. 2. In concealed fastenings for wall fixtures, a plate having a bridge fitted to the reverse side thereof, electrical connections extending through said bridge and projecting therefrom, said electrical connections being insulated from said bridge, a coupling element of insulating material, having conducting connections therein adapted to coöperate with said projections from the electrical connections, and further electrical connections adapted to lead from said coupling; an outlet box, a projection from said outlet box, and means for connecting said coupling to said projection.
15. 3. In concealed fastenings for wall fixtures, a plate having a bridge fitted to the reverse side thereof, electrical connections projecting from said bridge, one of said electrical connections being insulated from said bridge, a coupling element having receptacles therein adapted to coöperate with said projections from the bridge, and an electrical connection adapted to lead from said coupling; an outlet box, a threaded projection from said outlet box, on which said coupling is adapted to be screwed.
20. 4. In concealed fastenings for wall fixtures, a plate having a bridge fitted to the reverse side thereof, electrical connections extending through said bridge and projecting therefrom, said electrical connections being insulated from said bridge, a coupling element of insulating material, having conducting connections therein adapted to coöperate with said projections from the electrical connections, and further electrical connections adapted to lead from said coupling; an outlet box, and a threaded projection from said outlet box on which said coupling is adapted to be screwed.
25. 5. In concealed fastenings for wall fixtures, a plate having a bridge fitted to the reverse side thereof, electrical connections projecting from said bridge, said electrical connections being insulated from said bridge, a threaded coupling element having receptacles therein adapted to coöperate with said projections from the electrical connections, and further electrical connections adapted to connect with said projections and lead from said coupling; an outlet box, and a threaded projection from said outlet box on which said coupling is adapted to be screwed.
30. 6. In concealed fastenings for wall fixtures, a plate having a bridge fitted to the reverse side thereof, electrical connections projecting from said bridge, said electrical connections being insulated from said bridge, a coupling element having receptacles therein adapted to coöperate with said projections from the bridge, and an electrical connection adapted to lead from said coupling; an outlet box, a projection from said outlet box, and means for connecting said coupling to said projection.
35. 7. In concealed fastenings for wall fixtures, a plate having a bridge fitted to the reverse side thereof, electrical connections projecting from said bridge, said electrical connections being insulated from said bridge, a coupling element having receptacles therein adapted to coöperate with said projections from the electrical connections, and further electrical connections adapted to connect with said projections and to lead from said coupling; an outlet box, a projection from said outlet box, and means for connecting said coupling to said projection.
40. 8. In concealed fastenings for wall fixtures, a plate having a bridge fitted to the reverse side thereof, electrical connections projecting from said bridge, said electrical connections being insulated from said bridge, a coupling element having receptacles therein adapted to coöperate with said projections from the electrical connections, and further electrical connections adapted to connect with said projections and to lead from said coupling; an outlet box, a projection from said outlet box, and means for connecting said coupling to said projection.
45. 9. In concealed fastenings for wall fixtures, a plate having a bridge fitted to the reverse side thereof, electrical connections projecting from said bridge, said electrical connections being insulated from said bridge, a coupling element having receptacles therein adapted to coöperate with said projections from the electrical connections, and further electrical connections adapted to connect with said projections and to lead from said coupling; a support, a projection from said support, and means for connecting said coupling to said support.
50. 10. 5. In concealed fastenings for wall fixtures, a plate having a bridge fitted to the reverse side thereof, electrical connections
